(57) CLAIM

The ornamental design for a desk, as shown and described.

DESCRIPTION

FIG. 1 is a perspective view of a desk according to one embodiment of the design.

FIG. 2 is another perspective view of the desk of FIG. 1 with the drawer in an open position.

FIG. 3 is a front view of the desk of FIG. 1.

FIG. 4 is a rear view of the desk of FIG. 1.

FIG. 5 is a first side view of the desk of FIG. 1.

FIG. 6 is a second side view of the desk of FIG. 1.

FIG. 7 is a top view of the desk of FIG. 1.

FIG. 8 is a bottom view of the desk of FIG. 1.

FIG. 9 is a perspective view of a desk according to another embodiment of the design.

FIG. 10 is another perspective view of the desk of FIG. 9 with the drawer in an open position.

FIG. 11 is a front view of the desk of FIG. 9.

FIG. 12 is a rear view of the desk of FIG. 9.

FIG. 13 is a first side view of the desk of FIG. 9.

FIG. 14 is a second side view of the desk of FIG. 9.

FIG. 15 is a top view of the desk of FIG. 9; and,

FIG. 16 is a bottom view of the desk of FIG. 9.

Portions of the desk shown in broken lines are included for the purpose of illustrating environment and form no part of the claimed design.

1 Claim, 16 Drawing Sheets
